CLAIM

I claim the ornamental design for a battery pack, as shown and described.

DESCRIPTION

FIG. 1 is a front perspective view of a battery pack according to one embodiment of the invention.

FIG. 2 is a rear perspective view of the battery pack of FIG. 1.

FIG. 3 is a first side view of the battery pack of FIG. 1.

FIG. 4 is a second side view of the battery pack of FIG. 1.

FIG. 5 is a front view of the battery pack of FIG. 1.

FIG. 6 is a rear view of the battery pack of FIG. 1.

FIG. 7 is a top view of the battery pack of FIG. 1.

FIG. 8 is a bottom view of the battery pack of FIG. 1; and, FIG. 9 is another rear perspective view of the battery pack of FIG. 1.

Any portions of the battery pack shown in broken lines are included for the purpose of illustrating environment and form no part of the claimed design.
